UNITED STATES PATENT OFFICE.

F MARION SMITH, OF NASHVILLE, MICHIGAN, ASSIGNOR TO HUNTLEY MANUFACTURING COMPANY, OF SILVERCREEK, NEW YORK.

SHAKING GRAIN-SEPARATOR.

SPECIFICATION forming part of Letters Patent No. 766,538, dated August 2, 1904.

Application filed July 15, 1901. Serial No. 68,276. (No model.)

To all whom it may concern:

Be it known that I, F MARION SMITH, a citizen of the United States, and a resident of Nashville, in the county of Barry and State 5 of Michigan, have invented a new and useful Improvement in Shaking Grain-Separators, of which the following is a specification.

This invention relates to a machine for separating grains of different size wherein a shaking shoe or frame is provided with separating-screens, one below the other, and means for conveying the different grades of material over the screens and to the proper discharge-openings.

15 The machine herein described is especially useful for the separation of the hulled kernels of rice or oats from the unhulled kernels, usually called "paddy," which have to be returned to the hulling-machine.

20 The object of the invention is to produce a separating-machine of this character in which the shaking-shoe is provided with a novel combination of screens, conveyers, and cut-off valves for insuring a more thorough and 25 complete separation and a more convenient delivery of the separated materials.

In the accompanying drawings, Figure 1 is a longitudinal sectional elevation of a shaking separator embodying the invention. Fig. 2 30 is a transverse vertical section on line 2 2, Fig. 1. Fig. 3 is a horizontal section on line 3 3, Fig. 1. Fig. 4 is an enlarged sectional view of one of the cut-off valves. Fig. 5 is a side elevation of the adjusting device of the 35 cut-off valves. Fig. 6 is a fragmentary transverse section of the same on line 6 6, Fig. 5.

Like letters of reference refer to like parts in the several figures.

A represents the stationary frame of the 40 machine, of any usual or suitable construction; B, the feed-hopper arranged in the upper part of the frame at the front end thereof; C, the shaking-shoe, which is supported in any desirable manner in the frame below 45 the feed-hopper, as by flexible hangers e, and D an actuating-eccentric or the like connected with the shaking-shoe by a rod d or other suitable means.

The shoe C is provided with an upper screen E and a lower screen E', both inclined rearwardly. The upper screen E is arranged with its head end beneath the feed-hopper in position to receive the grain therefrom and is preferably provided with graded perforations, the smaller perforations being in the front 55 portion e of the screen and the larger perforations in the rear portion e'. The lower screen E' is shorter than the first screen E and is located beneath the rear portion e' thereof, extending from beneath the tail end 60 of the upper screen forwardly about half the length of the upper screen.

F is a conveyer-plate located beneath the front portion e of the upper screen E for receiving the hulled grain or clear separated 65 material passing through the same. This conveyer-plate is inclined rearwardly and terminates above the head of the lower screen E' at a vertical transverse partition f, which is provided with an opening f', extending above 70 and below the rear end of this conveyer-plate, so that the hulled grain falling upon the plate F is discharged rearwardly through said opening.

G is an upright spout or chute which is arranged in front of the lower screen and in front of the partition f and which connects at its lower end with a conveyer-plate H, located beneath the lower screen E' and inclined rearwardly. This plate H receives the hulled 80 grain or clear separated material from the lower screen and is provided near its rear end with a discharge-spout h for delivering the hulled grain.

I represents a rearwardly-inclined cut-off 85 conveyer-plate arranged underneath the rear portion e' of the upper screen and above the discharge-opening f' over the rear end of the front conveyer-plate F. This cut-off plate extends rearwardly nearly to a point beneath 90 the rear end of the upper screen.

J is a forwardly-inclined conveyer-plate arranged underneath the cut-off plate I for receiving the clear separated material from the same and extending from beneath the rear 95 end of the plate I to the upright spout G, so

that the hulled grain which falls upon this forwardly-inclined conveyer-plate J is delivered by the same to the spout G.

K represents a forwardly-inclined conveyer-plate which is arranged below the forwardly-inclined plate J and above the lower screen E' for conducting the cut-off material from the tail of the cut-off plate I to the lower screen. This plate K extends rearwardly beyond the rear end of the cut-off plate I and is provided at its rear end with an upright wall k, which extends upwardly to the tail end of the upper screen E. The front end of the plate K is separated from the rear wall of the spout G by a passage k', through which the material passes from the plate K to the head of the lower screen.

L is a cut-off conveyer-plate which is arranged beneath the lower screen E' and above the lower conveyer-plate H. This plate extends from the rear wall of the spout G rearwardly to a point beneath the tail end of the lower screen and receives the grain passing through the latter.

25 The upper cut-off plate I is provided with several cut-off openings, arranged one behind the other and extending across the plate. Each of these openings is controlled by a cut-off valve M in such manner that when the 30 valves are closed the plate is tight and discharges all of the material falling upon the plate over the tail end thereof, while when one of the valves is opened the material falling upon the portion of the plate above the open 35 valve passes through the opening and the material falling upon the plate below the open valve is cut off and discharged over the tail of the plate. The lower cut-off plate L is provided with similar cut-off openings and valves 40 N. These valves may be of any desirable construction and are each provided with a suitable fastening device for holding the valve open or closed. As shown in the drawings, Figs. 4, 5, and 6, the stem O of each valve extends through one of the side boards of the shaking-shoe and is provided on the outer side of the same with a segment p and handle p' for shifting the valve. A lug q is secured to the shoe and carries a clamping-screw q', which 45 engages the segment for holding the valve in the desired position.

In the operation of the machine the mixture of hulled and unhulled grain which is fed from the feed-hopper upon the head of the upper 55 screen is first separated by the front portion e of the upper screen, through which only hulled grain passes by reason of the smaller size of the hulled kernels. When the material reaches the rear portion e' of the upper screen it is all 60 ready impoverished in hulled kernels, and unhulled kernels are more liable to pass through this part of the screen, particularly toward the tail end thereof. At the point where unhulled grain or paddy begins to pass through the upper screen the cut-off valve M is opened, so that 65

the material which passes through the screen in rear of this open valve is cut off from the clear-hulled grain and sent to the tail end of the cut-off plate I, whence the material is conducted by the conveyer-plate K to the head of 70 the lower screen E'. In Fig. 1 the first cut-off valve M is shown open for this purpose, while the other valves are closed. The hulled grain which passes through the open valve of the cut-off plate I falls upon the conveyer-plate J, 75 which latter also receives the hulled grain which passes through the front portion e of the upper screen and falls upon the front conveyer-plate F. The hulled grain from the upper screen passes from the conveyer-plate J to the spout G and lower conveyer-plate H and is discharged through the delivery-spout h. The mixture of hulled and unhulled kernels which is delivered by the conveyer-plate K upon the head of the lower screen E' is further 80 separated by this screen, and as the lower cut-off plate L is also provided with cut-off valves this plate can be open at the point where paddy begins to pass through the lower screen, so that the mixed material is cut off at that point 85 and delivered over the tail end of this cut-off plate, while the clear-hulled grain passing through the front portion of the lower screen escapes through the open valve and joins the clear-hulled grain from the upper screen flowing over the lower conveyer-plate H.

The mixture of hulled and unhulled kernels can be delivered from the tail end of the lower cut-off plate L to a receptacle l', which also receives the paddy which tails off from the 90 upper and lower screens, or can be disposed of in any other suitable way.

The cut-off plates I and L are preferably constructed of wooden boards r and a sheet-metal covering s, and the cut-off valves are similarly composed of boards r' and a sheet-metal covering s', Figs. 4 and 6. The sheet-metal covering s of the plate projects rearwardly beyond the front edge of the cut-off opening, as shown at s², and is set back from the rear edge of the opening, as shown at s³. The sheet-metal covering s' of the valve is set back at the front edge of the valve and projects at the rear edge of the valve to fit against the edges of the sheet-metal covering 105 on the plate, so that when the valve is closed lapping joints are formed by the sheet-metal coverings of the plate and valves, whereby the joints between the boards of the valve and plate are closed. The lap-joints also serve to 110 hold the valves snugly in line with the plate when closed, so that the upper surface of the plate is smooth and presents no obstruction to the flow of the grain.

I claim as my invention—

1. The combination of a shaking-shoe, upper and lower rearwardly-inclined screens arranged therein, a rearwardly-inclined cut-off plate arranged underneath the upper screen and provided with one or more cut-offs which 120

can be opened or closed at will, a conductor for conveying the cut-off material from the tail end of said cut-off plate to the head of the lower screen, a rearwardly-inclined cut-off plate arranged underneath the lower screen and provided with one or more cut-offs which can be opened or closed at will, and conductors for the clear separated material arranged underneath said cut-off plates, substantially as set forth.

2. The combination of a shaking-shoe, an upper rearwardly-inclined screen arranged in the same, a rearwardly-inclined cut-off plate arranged underneath the rear portion of said screen and provided with a cut-off which can be opened or closed at will, a rearwardly-inclined conveyer-plate for the clear separated material arranged underneath the front portion of the upper screen, a forwardly-inclined conveyer-plate for the clear separated material arranged underneath said cut-off plate, a

rearwardly-inclined lower screen arranged in the rear portion of said shoe, a forwardly-inclined conveyer-plate conducting the cut-off material from the tail of said cut-off plate to the head of the lower screen, a lower rearwardly-inclined cut-off plate arranged underneath the lower screen and provided with a cut-off which can be opened or closed at will, a conveyer-plate for the clear separated material arranged underneath said lower cut-off plate, and a spout arranged in front of the lower screen for conducting the clear separated material from the upper screen to the conveyer-plate below the lower screen, substantially as set forth.

Witness my hand this 4th day of July, 1901.

F MARION SMITH.
